UNITED STATES PATENT OFFICE.

DAVIDSON S. HAYNES, OF EVANSVILLE, INDIANA.

TIMER.

1,416,638.

Specification of Letters Patent. Patented May 16, 1922.

Application filed April 2, 1920. Serial No. 370,700.

To all whom it may concern:

Be it known that I, DAVIDSON S. HAYNES, a citizen of the United States, and resident of Evansville, county of Vanderburgh, State 5 of Indiana, have invented certain new and useful Improvements in a Timer, of which the following is a specification.

It is well appreciated that timers now upon the market have one inherent defect in 10 that in both sliding and rolling contact timers the friction between the various parts renders a renewal of the same imperative after the power plant with which they are associated has been operated for a certain 15 length of time.

Another defect, particularly noticeable in 20 connection with the timer utilized on automotive vehicles of the Ford type, has been that certain of the wires leading from such timer are liable to come in contact with moving parts of the power plant, resulting in a stripping in the insulation from such wires and a subsequent defect in the operation of 25 the power plant.

With a view of avoiding the first-named 30 defect constructions have been proposed embodying a circuit making and breaking means not relying upon a sliding or rolling contact, but these timers have proven inefficient in that it has been difficult and consequently expensive to manufacture the parts 35 of which the same are comprised and particularly to assemble such parts to form a complete unit.

With a view of overcoming these difficulties I have constructed a timer which 40 shall embody circuit making and breaking parts not relying on a sliding or rolling contact, which parts shall be extremely simple in construction and permit of great ease in assembling.

A further object of my invention is the 45 construction of a timer avoiding the difficulty heretofore experienced in that the various lead wires running from the same are so disposed that certain of them are liable to come in contact with moving parts of the power plant.

A still further object of my invention is 50 the construction of a timer of the Ford type which will permit the use of a smaller cam, thus reducing the wear on the surface of the cam and the parts contacting with the same.

Further objects of my invention will be 55 come apparent upon reference to the enclosed specification and drawings which latter rep-

resent one practical embodiment of my invention, and in which—

Figure 1. is a plan view, partly in section, of a timer constructed in accordance with 60 my invention;

Figure 2. is a side view thereof,

Figure 3. is a sectional view therethrough, and

Figures 4. and 5. are perspective and 65 enlarged sectional views of certain details of construction employed by myself in forming the timer.

In all of these views like reference numerals designate similar parts and the reference numeral 10 indicates the cap of a timer formed with a flange 10' and from 70 which project lead wires as at 11, which lead wires it will be noted extend through only a short portion of the body of the timer thus 75 eliminating the difficulty heretofore experienced and brought out in the preamble, where the four lead wires are merged approximately 90° apart. By this construction it will be possible to have all of the 80 lead wires 11 passing through the walls of the cap 10 at a point remote from the moving parts of the power plant, and the same may subsequently be united by means of an insulated tubing 12 to present a compact unit 85 at all times.

Extending parallel to the side walls of the 90 cap 10 and within the same may be an annular flange, such as 13, which adjacent to its point of connection with the inner face of the cap 10 is formed with a groove 14, for a purpose hereinafter more fully specified.

An assembly ring 15 is formed with an annular flange 16 adjacent one of its edges and is provided with split portion 17. Adjacent to both the outer edges of the said ring 15 the same is formed with inwardly extending flanges 18, between which extend 95 shafts 19, corresponding in number to the number of leads employed. Each of the 100 shafts 19 rockingly mounts a yoke-like member 20, one arm of which is formed with a contact surface 21 in a line with a contact point 22 formed by a conventional lead terminal projecting through the ring 15. A 105 spring 23 of any desired construction cooperates with the yoke members 22 and serves to firmly cause the contact surface 21 thereof to be pressed into engagement with the contact point 22 formed by the terminal. 110

The arm opposite to the arm carrying the contact surface 21 of the yoke-like members

extends inwardly as has been clearly shown in Figure 1, and presses against the outer surface of a conventional cam 24 and it will be noted that upon a rotation of the latter 5 that the yoke-like members will be permitted to rock around their shafts 19 by virtue of the springs 23 and contact surface 21 will be brought successfully to bear 10 against the contact points of the terminals 22.

It is to be noted that any suitable type of current conducting members, such as wires 25, are used to connect the terminals 22 with the lead wires 11, in that one of the ends of 15 each of the wires 25 is attached to the former, its opposite end being connected to the latter.

It will be well appreciated that it will be an extremely simple matter to assemble 20 the yoke-like members 20 upon their shafts 19 within the ring 15 when the same is extraneous of the cap 10.

Subsequent to such assemblage the ring 15 is contracted, this being permitted by the 25 split portion 17, thereof, and the ring is inserted into the cap 10 until the flange 16 is adjacent the groove 14 of the cap at which point the ring is permitted to extend so that the flange 16 thereof enters the groove 14 30 and the outer face of such ring lies flush against the inner face of the flange 13.

Now with a view of retaining the ring 15 immovable with respect to the cap 10, one of the flanges 18 has its end, i. e. the portions 35 adjacent the split part 17, flared outwardly with respect to one another, as has been indicated at 26, and a screw can now be inserted between the ends of such flange and in an opening formed in the cap 10, the flared 40 head of such screw bearing against the out-turned ends of such flange, and upon being tightened against the same will expand the ring 15 against the inner face of the flange 13 and thus render the same immovable with 45 respect thereto.

From the foregoing it will be appreciated that I have constructed a timer, the lead wires of which will not in any way interfere with the moving parts of the power 50 plant with which the same is associated. Further, a timer is constructed which will have none of the inherent defects of a sliding

or rolling contact timer and which will, nevertheless, permit an assemblage of the parts with great ease.

Obviously, numerous modifications of structure might be resorted to without departing from the scope of my claims, which are—

I claim:

1. A timer including a cap, a ring within said cap, inwardly extending flanges forming a part of said ring, yokes rockingly mounted between said flanges, contact surfaces upon one of the arms of said yokes, 65 lead terminals forming contact points in line with the contact surfaces of said yoke arms and means for rocking such yoke arms.

2. A timer including a cap, an annular flange within said cap and forming a part 70 of the same, the inner face of such flange being formed with an annular groove adjacent its point of connection with the cap, a ring formed with an outwardly extending flange adjacent one of its edges and inwardly 75 extending flanges adjacent both of the same, shafts extending between such inwardly extending flanges, yokes rockingly mounted upon such shafts, one of the arms of each of 80 said yokes being formed with a contact surface, lead terminals projecting through said ring and terminating in contact points in line with such surfaces, springs associated with each of said yokes tending to normally 85 cause contact between such surfaces and 90 points, means for opening and closing such contacts, said ring being adapted to bear against the inner face of the cap flange, the outwardly extending flange of such ring seating within said annular groove.

3. A timer including a cap formed with an annular flange, such cap being provided with an annular groove adjacent its point of connection with the cap, a ring formed with an outwardly extending flange adjacent one 95 of its edges, such ring being split and carrying circuit making and breaking means, said ring being adapted to be positioned within said cap and have its flange extending into said annular groove and means connected 100 to said cap for extending such ring and forcing the outer face of the same against the inner face of the annular groove and flange.

DAVIDSON S. HAYNES.
